FOREIGN PATENT DOCUMENTS

GB 2106580 4/1983

Primary Examiner—Cathron Brooks*Assistant Examiner*—Barbara Fox(74) *Attorney, Agent, or Firm*—Wood, Herron & Evans, LLP(57) **CLAIM**

The ornamental design for a window grille clip, as shown and described.

DESCRIPTION

FIG. 1 is a perspective view of a window grille clip according to this invention and shown on a window grille drawn in phantom lines.

FIG. 2 is an enlarged perspective view of the window grille clip of FIG. 1.

FIG. 3 is a front elevational view thereof.

FIG. 4 is a left side elevational view thereof with the right side view being a mirror image thereof.

FIG. 5 is a rear elevational view thereof.

FIG. 6 is a top plan view thereof; and,

FIG. 7 is a bottom plan view thereof.

The broken lines in the drawings represent unclaimed subject matter.
